UNITED STATES PATENT OFFICE.

JOSEPH P. SAUER, OF WHEATON, ILLINOIS.

ELECTRICAL SIGNALING SYSTEM.

No. 904,018.

Specification of Letters Patent. Patented Nov. 17, 1908.

Application filed April 10, 1906. Serial No. 310,944.

To all whom it may concern:

Be it known that I, JOSEPH P. SAUER, a citizen of the United States, residing at Wheaton, in the county of DuPage and State of Illinois, have invented certain new and useful Improvements in Electrical Signaling Systems, of which the following is a specification.

This invention relates to improvements in electric signaling systems, and refers more particularly to a system adapted for signaling for either steam, electric or other railroads.

Among the salient objects of the invention are to provide a system especially suitable for use in connection with electric currents of high tension, the circuits and magnets being so arranged and designed as to obviate difficulties due to arcing and other objectionable features likely to accompany the use of high tension current; to provide in a system of this character improved circuits which enable lamps to be used as resistance, and this resistance used in common for two blocks pertaining to two tracks running side by side; to so arrange the lamps used as resistance that they will at the same time perform the function of a visual signal; to provide for use in conjunction with the system a non-arcing relay; to provide for use in conjunction with the system a non-arcing ringer or bell; to provide improvements in the mechanically actuated contact devices, whereby the signaling system is controlled; and in general to provide improvements in a system of the character referred to.

To the above ends the invention consists in the matters hereinafter described, and more particularly pointed out in the appended claims.

The invention will be readily understood from the following description, reference being had to the accompanying drawings, in which—

Figure 1 is a plan view of the non-arcing relay forming one feature of the invention; the relay being shown as inclosed in a casing, the cover of which is removed; Fig. 2 is a sectional view taken on line 2—2 of Fig.

1, looking in the direction of the arrows and showing the relay in side elevation; Fig. 3 is an end elevation of the relay removed from the casing and looking at the armature end thereof; Fig. 4 is a sectional detail of

one of the fixed contacts of the relay; Fig. 5 is a further detail of the same taken on line 5—5 of Fig. 4; Fig. 6 is a plan view of the non-arcing ringer or bell; the cover or top casing and gong being removed; Fig. 7 is a sectional view taken on the plane indicated by line 7—7 of Fig. 6 in so far as the casing and gong are concerned but showing the bell magnet and operative mechanism thereof in side elevation; Fig. 8 is an end elevation of the ringer magnet looking at the armature end thereof; Fig. 9 is a sectional detail of one end of the striker; Fig. 10 is a diagrammatic view showing the electrical connections of one embodiment of the invention wherein it is shown as used in conjunction with a third rail electric railway and on double tracks each traversed one way only; Fig. 11 is another diagrammatic view showing the application of the invention to a single track overhead trolley road, traversed in both directions; Fig. 12 is a detail of an overhead trolley contact device used in conjunction with the system but forming no part of the present invention.

First describing the several mechanical devices used in connection with the system, and referring to Figs. 1 to 5, inclusive, 1 designates as a whole a suitable weather-proof casing, desirably provided with a removable top or cover plate 2, and within which casing is arranged a non-arcing relay designated as a whole 3. This relay comprises a suitable heel-piece 4 upon which are mounted the magnet spools 5 and 6, a yoke plate 7 mounted flatwise upon the pole piece ends of the spools and surrounding the cores indicated in dotted lines at 8 of the spools, a flat pole piece 9 lying immediately outside and against the yoke plate 7, and an armature, designated as a whole 10, which takes the form of a plate-like member having outturned pivot trunnions 11 which engage corresponding pivot apertures 12 in ears formed integrally with the yoke piece. The yoke piece is, as usual, of brass or other non-magnetic metal. The armature 10 carries at its swinging edge a pair of carbon contacts 13, which are spring supported upon the armature; a bow spring 14 being to this end rigidly connected with the central part of the side of the armature by means of a screw 15 and suitably insulated from the armature by means of the usual

bushing and insulating washers 17 and 18. In order to permit the contact devices 13 to close circuit while the armature is still relatively distant from the pole piece, the spring 14 is made comparatively weak, and a reinforcing spring 19 is arranged along side of the spring 14 which comes into action and is brought under tension when the armature has nearly reached its limit of closing movement, thereby insuring a more reliable contact than would be produced by the weaker spring 14 alone. The springs 14 and 19 are mounted upon the same supports and may be considered as a single leaf spring. 15 Coöperating carbon contacts 20, 20, are mounted in position to engage the contacts 13; in the improved construction shown these contacts 20 being adjustably mounted upon slotted ears or arms 21 formed integrally with the yoke plate 7. Each contact device 20 comprises an adjustable plate 22 adjustably mounted upon the corresponding ear 21 by means of a screw 23 and insulated therefrom by a bushing and washer 24 and 25; the plate 22 being formed to provide a socket 22' within which the carbon block 20 is seated, as shown clearly in detail Figs. 4 and 5.

A limiting stop is provided for arresting the armature in its movement away from the pole pieces; this stop mechanism comprising a bent arm 26 secured to the central part of the yoke plate between the spools, extending thence out around the edge of the yoke and armature and returned opposite the latter (see Fig. 2), and carrying at its end an adjusting stop screw 27, the end of which directly impinges against the armature.

40 The relay is conveniently supported in fixed relation in the casing by means of a pair of screws 28 inserted through the casing and threaded into the heel pieces. In this connection it is to be noted that the relay may be removed bodily from the casing without disturbing any of the electrical connections by simply removing the two screws 28. It is further to be noted that in use the relay will be used in the position indicated in 45 Figs. 1 and 2, *i. e.* with the armature end of the relay downward so that the armature falls into open circuit position by gravity.

Describing now the ringer, and referring to Figs. 7 to 9, inclusive, 29 designates as a 55 whole a suitable weatherproof casing desirably provided with a removable plate-like cover 30, the central portion of which is outwardly convex and serves as a support upon which is rigidly mounted a gong 31. Inside 60 of the casing is arranged the ringer magnet and mechanism, comprising a plate-like heel piece 32 fixedly secured to the end wall of the casing, a pair of magnet spools 33, a plate-like yoke 34, a pole piece 35 mounted 65 upon the ends of the cores of the magnet

which project through the yoke, and a plate-like armature 36. The armature 36 is provided at two of its corners with pivot trunnions 37 which engage diagonally disposed pivot slots 38 formed in ears 39 integral with the yoke 34.

Connected with the central portion of that side of the armature remote from the pivots is the striker 40 which desirably has the form of a straight rod carrying at its outer end an enlarged head 41 which is adjustably threaded upon the rod-like body 40, as indicated at 42. The striker has a spring connection with the armature permitting it to rebound instantly after encountering the gong and before the armature is released, thereby insuring clear ringing. To this end the attached end of the striker rod has a reduced neck portion 43 working through an aperture in the armature, and between the head 44 upon the end of this reduced portion and the armature is interposed a plate spring 45 (see Figs. 7 and 8) which effects the rebound of the striker, as described.

90 The armature is forced into open position by means of a coil contractile spring 46 having one end connected with an extension 47 of the armature and its opposite end connected with an adjusting link 48 extended through a suitable aperture in the casing and held in adjusted position by means of a nut 49. In order to limit the throw of the armature, the stop arm 50 is connected with the central part of the yoke plate, carried 95 thence out around the edge of the armature and returned opposite the latter, and through the end of this arm is threaded an adjusting stop screw 51 which impinges the spring 45, as seen clearly in Fig. 7.

100 Brass cushion stops 52 are seated in the armature not far removed from the pivotal axis of the latter so as to encounter the pole piece during an early part of the closing movement of the armature. During the 105 movement after the cushions engage the pole piece, the armature fulcrums upon these cushions and the pivot trunnions travel in the slots 38. The object of this peculiar arrangement is to insure a stronger initial 110 closing movement of the armature by bringing the heel of the armature and pole piece almost or quite into contact with each other; the cushions nevertheless acting effectively 115 to prevent sticking of the armature and insure its prompt return.

120 The important characteristic of this ringer is that its armature is actuated without at any time opening the electric circuit, and thus sparking or arcing is avoided. 125 This is accomplished by shunting out the magnet each time the armature closes, as distinguished from opening the circuit by the closing of the armature. Obviously the armature itself is the most suitable member 130

for actuating the contacts which effect this shunting of the circuit, and the movable contact is accordingly mounted to move with the armature. Inasmuch, however, as the 5 armature is necessarily a relatively heavy member it is desirable that it be cushioned in its closing movement so as to prevent unnecessary and destructive pounding, and accordingly one of the important features of 10 the present invention resides in providing yieldably closing contacts which permit the armature to continue its movement under the action of inertia or momentum, after the contacts have actually come together and 15 the circuit been thereby shunted and the magnet deenergized. In carrying out this feature of the invention I mount one contact 53 on a spring 54 carried by the armature and a coöperative contact 55 upon a V- 20 spring 56 carried by an extension 57 of the yoke 34. The engaging parts of the contact devices 53 and 55 are desirably carbon blocks, and the relative disposition of the springs 54 and 56 is such that these carbon 25 bodies have a slight rubbing movement upon each other after they are brought together and during the further movement of the armature. The yieldability of the contacts secures the advantage hereinbefore 30 described, and the rubbing movement insures a more perfect electrical contact than would ensue if the contacting points were brought squarely together without rubbing movement.

35 Binding posts 57 and 58 are mounted upon the exterior of the casing for connection with the leading-in wire and magnet; one of these binding posts being insulated and the other directly connected with "frame." 40 Describing now the circuits forming one feature of the invention, and referring first to diagrammatic Fig. 10, two of the non-arcing relays hereinbefore described are designated by the letters A and A', and one of 45 the ringers by the letter B; these instruments being shown diagrammatically. a, a' designate one pair of track rails which are to be traversed by the car from right to left as indicated by the arrow, and b, b', a second 50 pair of track rails which are traversed in the reverse direction.

C designates as a whole any suitable source of electric current, the diagram indicating conventionally a dynamo, one side of which 55 is grounded, as indicated at 59.

60 and 61 designate conductors extending along the respective tracks, which conductors may be third rails, and the generator C is connected with each of these conductors by 60 means of leads 62 and 63. The arrangement shown in this figure is one in which the signal device B (the ringer in this instance, although it might be any other suitable form of annunciator) is located in the middle of 65 the block and is common to both tracks. The

relays A and A' which control said annunciator are also conveniently located near the ringer.

Means are provided for closing a circuit and setting the ringer into operation whenever a car enters the block at either end, and for continuing this operation until the car has reached a point substantially opposite the ringer or near the middle of the block, at which point the ringer is again thrown out of operation: such an arrangement being well suited for guarding a crossing.

Describing now the circuits and mechanism for effecting this operation, at the entrance point of each block is located a mechanically actuated circuit closing device adapted to be moved to close the circuit by the engagement therewith of one of the track wheels of the approaching car; these instruments being designated as a whole D 70 and E, respectively. Similarly constructed cut-out instruments F and G, respectively, are located along the respective tracks at about the middle of the block. Each of said track instruments comprises a main lever 80 85 pivoted at one end, as indicated at 65, to a suitable support, and having its upper surface normally projecting slightly above the tread surface of the adjacent track rail, the contacting surfaces of these main levers 90 being inclined upwardly and forwardly so that as the car wheels traverse over the lever it will be gradually depressed and not struck too abrupt a blow. The moving end of the lever E engages a second contact lever 66 100 pivoted between its ends, as indicated at 67, and carrying at its opposite end a contact device 68; the coöperative arrangement of the two levers being such that the movement of the end of lever 64 is multiplied at the 105 end of lever 66. The levers 66 are normally held retracted by means of contractile springs 69. Upon a suitable insulating support in proper relation to the contacts 68 of the several levers 66 are mounted fixed 110 contacts 70. The contacts 68 of the instruments E and G are electrically connected by means of conductors 71 with the third rail 61 and the contacts device 70 of the instruments F and D are electrically connected 115 with the third rail 60.

From the contact device 70 of instrument E a conductor 72 leads to the contact device 20 of relay A, thence through the windings of the relay, thence through a relatively 120 small resistance 73, and from there to and through a higher resistance, preferably consisting of a series of lamps 74. From a point beyond the resistance 74 a conductor 75 leads to the binding post 57 of the ringer, 125 from which binding post a conductor 76 leads to and through the windings of the ringer magnet and to the binding post 58. From the latter a conductor 77 leads to ground at 78. An alternative electric path 130

leads from the binding post 57 to the back contact 55 of the ringer, from the latter to the moving contact 53, and from the latter, which is connected to "frame," to the binding post 58 and to ground as before. This latter alternative path, it will be noted, short circuits the windings of the ringer magnet when the armature is in closed position.

From one of the third rail or track conductors, that designated 60 in the present instance, a conductor 79 leads to the contact 20' of relay A and thus provides another source of current for maintaining said relay energized. That is to say, when the circuit 10 is momentarily closed at track instrument E by the passage of a car, the armature of relay A moves into closed position and in so doing closes a holding circuit from the third rail 60 over conductor 79 through contact 20', and the armature of the relay to contact 20, and thence through the windings of the relay and to ground beyond the bell as hereinbefore traced.

When the car wheel encounters track instrument G and closes the latter, a circuit is 25 established which short circuits or robs relay A of current, and permits it to return to its deenergized position. This circuit is from contact 70 of instrument G over a conductor 80 to a point on conductor 72 between the rail A and the main resistance 74. Bearing in mind that the holding circuit through conductor 79 is maintaining relay A closed, it will be obvious that when the circuit over 30 conductor 80 is established as last described the potential on opposite sides of said relay A will be practically equalized, thereby permitting the armature of the latter to drop back without sparking or arcing as its armature leaves the back contacts.

In a precisely similar manner the relay A' is connected with the track instrument D by means of a conductor 81 which leads to and through the relay, thence through the relatively small resistance 73', thence to and through a high resistance 74', and thence to and through the ringer B. The conductor 79 connects with the contact 20' of relay A', thus serving as a common holding circuit for 45 both relays. The short circuiting or cut-out track instrument F is connected with conductor 81 by a conductor 82 in a manner corresponding precisely to the relays between conductors 80 and 72.

50 It will be noted that both of the relays A and A' and the ringer B are actuated and perform their functions without at any time tending to spark or create arcs between their contacts, and this will be true even though 55 the potential used is extremely high.

Describing now the application of the invention to an overhead trolley system, and referring to Fig. 11, A'' and B' designate, respectively, the relays and ringer, C' a generator or other suitable source of current,

and c, c', track rails of a track that would be traversed in both directions by cars.

H designates as a whole a contact device which may advantageously be used for closing the circuit between the trolley wire and the conductors pertaining to the signaling system. Describing said instrument, 83 designates a yoke connected between the ends of the cross supporting wires 84, and, as usual, insulated from the latter by means of insulating links 85. The central portion of the yoke 83 is provided with a vertical socket 86 within which is arranged to reciprocate a headed plunger 87, the lower end of which is clamped upon the trolley wire 88 and thus supports the latter. In the upper end of the socket 86 is seated an insulating block 89, and in this block is movably seated a secondary plunger or contact device 90, the lower end of which depends below the block 89 in position to be engaged by the head of the plunger 87 when the latter is raised. The upper end of the contact device 90 rests in engagement with a contact strip 91 which is mounted upon an insulating disk 92 in 90 closed in a cap 93 threaded upon the upper part of the hanger. The connecting conductor leads in through the side of the cap 93 and is attached to contact strip 91; an insulating bushing 97 being arranged to insulate the leading in conductor from the cap. 95

In the diagrammatic Fig. 11 these contact devices are again designated H; but in said view the cross wires which support them are omitted in order to avoid confusing the 100 showing of the circuits. It is to be understood, however, that they will be arranged in substantially the same manner as the usual cross wire supports, but will be tensioned less tightly than the main supporting cross 105 wires, so that the trolley wire may sag slightly at the points where they are applied and thus normally hold the plungers 87 and 90 out of contact with each other. As the trolley wheel traverses along under each 110 contact device, and thus raises the trolley wire, the circuit will be closed between the plungers 87 and 90.

Describing now the circuits, from the contact devices H, H, at the remote ends of the 115 signal block lead conductors 95 and 96 which meet at a point 97 and there connect with a conductor 98 common to both. The conductor 98 leads to a point 99 at which two branches 100 and 101 lead respectively to 120 and through the relay A'' and to and through the ringer B'. The contact devices H first closed by a car entering the block in either direction are in fact the cut-out contacts and serve only momentarily to energize the ringer while the relay is not energized at all because a circuit is not completed therethrough, as will hereinafter appear. The contact devices H' next encountered are connected by means of conductors 102 and 130

103, respectively, with a common conductor 104 which leads to the contact device 20 of the relay, and thence through the windings of the relay to a small resistance 105 and 5 from the latter through a high resistance 106 (preferably a series of lamps) and to the binding post 57 of the ringer. From thence the circuit is through the ringer, as described in connection with the diagram 10 shown in Fig. 10. The contact device 20 of the relay is permanently connected with the trolley wire by means of a conductor 107 which forms the holding circuit conductor, corresponding to that designated 79 in the 15 previous diagram.

From a contact device H'' located mid-length of the block a conductor 108 leads to and is connected with the conductors extending between the relay and ringer, as indicated at 99. This conductor completes a circuit which short circuits the relay and allows the latter to open, thus stopping the operation of the ringer as the car reaches the middle portion of the block when passing in 25 either direction.

A complete cycle of operations brought about by the passage of the car over the track in either direction will be as follows: When the car encounters the first contact device H , a circuit will be established from ground at the generator through the latter, the trolley wire and thence to ground through the ringer, which will cause the ringer to operate only as long as the contact device H is held closed by the trolley wheel, and this will obviously be but momentarily if the car is progressing. Upon arriving at the contact device H' , a circuit will be closed through the relay momentarily, and the holding circuit through conductor 107 will now 40 come into operation and maintain the relay closed and maintain the bell in operation until the contact device H'' located near the center of the block is closed. Thereupon the conductors 107 and 108 being both in circuit with the trolley wire the potential on the two sides of the relay will be substantially equalized and the relay will open, thus 45 interrupting the operation of the bell as soon as the contact device H'' opens. When the trolley wheel closes the contact between the contact device H' and the trolley in passing out of the block, the relay will be again closed and the bell will continue to operate 50 until the trolley wheel closes the contact at H in passing out of the block. The closing of the last mentioned contact will again equalize the potential on the two sides of the relay, thus opening the latter and arresting 55 the operation of the bell as the contact device H opens. It is to be noted in this connection that when the relay is in circuit through both conductors 107 and 95, as it 60 will be momentarily, the flow of current through the relay will be reduced in the pro-

portion that the total resistance of the lamps 105, the windings of the relay and the conductor 107 bear to the resistance of conductor 95 alone. This condition so robs the flow of current through the relay as to amount to 70 practically short circuiting it.

I claim as my invention:

1. In an electric system, the combination of a controlling relay, a second electrically actuated instrument controlled by said relay, 75 a source of electric current, means for establishing a temporary circuit through the relay, means for establishing a holding circuit through the relay and supplying current to said second instrument, and means for establishing a circuit operating to neutralize the armature holding induction of the relay to effect the opening of the latter without accompanying disruptive discharge. 80

2. In an electric system, the combination of a controlling relay, a second electrically actuated instrument controlled by said relay, 85 a source of electric current, a mechanically actuated contact device and associated means for establishing a temporary circuit through the relay, means for establishing a holding circuit through the relay and through said second instrument, and a mechanically actuated contact device and associated means for establishing a circuit operating to neutralize the armature holding induction of the relay to effect the opening of the latter without 90 disruptive discharge and interrupting the operation of said second instrument. 95

3. In an electric system, the combination with a length of railway track and a source of current arranged along said track, of a controlling relay, an electrically actuated annunciator controlled by said relay, a mechanically actuated track instrument and 105 associated conductors for establishing a temporary circuit through the relay, means for establishing a holding circuit through the relay and said annunciator upon the closing of the relay, and a second track instrument 110 and associated conductors for establishing a circuit operating to neutralize the armature holding induction of the relay to effect the interruption of said holding circuit without 115 disruptive discharge. 120

4. In an electric system, the combination of a length of track and an energized supply conductor extending along said track, of a controlling relay, an annunciator in series with said relay, a mechanically actuated normally open track instrument and associated conductors for establishing a temporary circuit through said relay, a holding circuit conductor connected with said supply conductor, contacts controlled by the armature 125 of the relay for establishing a holding circuit through the latter and said holding circuit conductor upon the closing of the relay, a second normally open mechanically actuated track instrument, and a conductor lead- 130

ing thence to and connecting with the holding circuit at a point between the relay and annunciator and operating when closed to neutralize the armature holding induction of 5 the relay.

5. In an electric system, the combination of a length of track and an energized supply conductor extending along said track, of a controlling relay, an annunciator arranged 10 in a normally open circuit controlled by said relay, a mechanically actuated normally open track instrument adapted to be closed by the passage of a car, a conductor leading from said track instrument to and through 15 said relay and thence to ground, a holding circuit conductor permanently connected with said supply conductor, a normally open contact associated with said relay and connected with said holding circuit conductor, 20 means operable by the armature of the relay for establishing a holding circuit through said holding circuit conductor and the relay, a second track instrument, and a shunting conductor connecting said latter instrument 25 and a part of the holding circuit to substantially short circuit the relay.

6. In an electric system, the combination of a length of track and an energized supply conductor extending along said track, of a controlling relay, a pair of contacts and an armature adapted to bridge or connect said contacts associated with said relay, an annunciator in series with said relay, a ground connection electrically beyond the relay and 30 annunciator, a normally open mechanically actuated track instrument adapted to be closed by the passage of a car over the track, a conductor extending from said track instrument to one of said relay contacts and 35 thence through the relay windings for temporarily energizing the latter, a holding circuit conductor permanently connected with said supply conductor and extending thence to and connected with the second of said relay contacts, whereby a holding circuit is 40 established through the relay when the latter closes, a second normally open track instrument, and a conductor extending from said latter instrument to and connected with the 45 holding circuit at a point between the relay and ground.

7. In an electric system, the combination with a length of track and an energized supply conductor extending along said track, of 55 a block signaling system comprising a controlling relay, an annunciator, a mechanically actuated normally open track instrument located near the entrance to said block, a conductor connected with said track instrument leading thence to and through the relay, and thence to and through the annunciator and thence to ground, a resistance interposed between the relay and annunciator, a holding circuit conductor connected with 60 said supply conductor and with a normally 65

open contact associated with the relay, a bridging conductor moving with the armature of the relay and adapted to extend the circuit from the holding circuit contact to and through the relay windings, a second 70 normally open mechanically actuated instrument located intermediate the length of the block, and a conductor connected with the latter instrument and extending thence to and connected with the circuit conductor 75 extending between the relay and annunciator at a point between the relay and the main resistance in said circuit.

8. The combination with a railway, and a length of energized supply conductor extending along said railway, of a block signaling system comprising a controlling relay, an annunciator, two longitudinally separated track instruments located near each other at each end of said block system, the inner one 85 of each pair of said instruments constituting a cut-in instrument and the outer one of each pair constituting a cut-out instrument, cut-in conductors leading from each cut-in instrument to a common conductor and 90 thence through the relay, thence through the annunciator and to ground, a pair of normally open contacts and a bridging conductor associated with the armature of said relay, a holding circuit conductor permanently 95 connected to the supply conductor and to one of said normally open contacts whereby upon the closing of the relay a holding circuit is established through the latter, cut-out conductors connected with each of the cut-out 100 instruments and extending thence to and connected with each other, and a common conductor connecting the cut-out conductors with the conductor extending through the relay and annunciator at a point electrically 105 between said latter instruments.

9. A non-arching relay and circuit therefor comprising a magnet coil, an armature operable thereby, a pair of relatively stationary contacts, a supply conductor connected with one of said contacts and leading thence through the windings of the coil, a return circuit conductor connected with the opposite side of the coil, a second supply conductor connected with the other of said contacts, a 110 bridging conductor moving with the armature of the magnet and operating to close the circuit between said relatively stationary contacts when the armature is in closed position, a short circuiting conductor adapted to 115 be connected with the source of supply and with the return circuit conductor, and means for closing and opening the circuit through said short circuiting conductor.

10. A non-arching relay and circuit therefor 120 comprising a magnet coil, an armature operable thereby, a relatively stationary contact, a supply conductor connected with said contact and leading thence through the windings of the coil, a return circuit conductor 125 connected with the source of supply and with the return circuit conductor, and means 130

nected with the opposite side of the coil, a second supply conductor, means controlled by the armature for electrically connecting said second supply conductor with said contact, a short circuiting conductor adapted to be connected with the source of supply and with the return circuit conductor, and means

for closing and opening the circuit through said first supply conductor and through said short circuiting conductor.
